METHOD OF AND APPARATUS FOR COMPRESSING FLUID.

1,283,593.

Specification of Letters Patent.

Patented Nov. 5, 1918.

Application filed July 16, 1917. Serial No. 180,873.

To all whom it may concern:

Be it known that I, ROBERT SUCZEK, a subject of the Emperor of Austria-Hungary, residing in the city of Philadelphia, county of 5 Philadelphia, and State of Pennsylvania, have invented certain new and useful Improvements in Methods of and Apparatus for Compressing Fluid, of which the following is a specification.

10 My invention relates to a method of and apparatus for compressing elastic fluid by operating thereon upon the ejector principle in a plurality of stages by elastic motive fluid, such as steam.

15 It is the object of my invention to provide a method and apparatus for compressing elastic fluid from a vacuum of 25 inches or higher, as measured on the mercury column, to suitable higher pressure, as atmospheric 20 pressure or higher, at higher efficiency than heretofore attainable, that is, by reducing the amount of motive fluid per unit of elastic fluid compressed.

25 The load upon an ejector, that is, the amount of elastic fluid compressed, varies in practice over considerable range. With a given steam or motive fluid consumption and an increase in the load the absolute pressure at the suction inlet of the ejector rises; for 30 example, where more air is to be removed from a steam condenser or the like with a given steam consumption the pressure in the condenser will rise, that is, the vacuum will become less.

35 I have found that in vacuum producing ejector apparatus the ratio of compression in the first stage should be equal to or preferably greater than the ratio of compression in the second stage for all variations of load 40 which cause variations in the initial pressure of the elastic fluid to be compressed ranging over approximately one-sixth or less of the entire range from zero absolute pressure to the pressure to which the elastic fluid is compressed.

45 Accordingly, by my invention, whatever the type of the ejector apparatus, I so proportion the total throat area of the nozzle or nozzles in the first stage to the total throat 50 area of the nozzle or nozzles in the second stage that in the first stage there will be consumed more than five per cent. of the total motive fluid of both stages. With this con-

dition of motive fluid consumption obtaining, there will be obtained a ratio of compression in the first stage equal to or greater than the ratio of compression in the second stage, provided the load varies only between those limits causing the initial pressure of the fluid to be compressed to vary only 55 within approximately one-sixth or less of the entire range from zero absolute pressure to the pressure to which the elastic fluid is compressed. Through the remainder of the total range through which the elastic fluid is compressed, however, the relation of the ratios of compression in the two stages is reversed in that in the first stage the ratio of compression is less than in the second stage. I have found that the most efficient operation of the 60 apparatus is obtained when the ratio of compression in the first stage is equal to the ratio of compression in the second stage for a load causing at the suction inlet of the first stage a vacuum of 25 inches or higher, or 65 within the first sixth of the entire range from zero absolute pressure to the pressure to which the elastic fluid is compressed.

70 For an illustration of some of the forms my apparatus may take and for an illustration of some of the forms of apparatus suitable for carrying out my method, reference is to be had to the accompanying drawing, in which:

75 Figure 1 is a graphic representation of the relation between the ratios of the compression ratios of both stages and pressures at the suction inlet of the first stage ejector.

Fig. 2 is a sectional view, parts in elevation, of double stage apparatus embodying 80 my invention.

Fig. 3 is a horizontal sectional view illustrating the arrangement of nozzles in the first stage of Fig. 2.

Fig. 4 is a fragmentary sectional view, 95 partly in elevation, of nozzles and diffuser suitable for employment in my apparatus, and particularly in the first stage thereof.

Fig. 5 is a horizontal sectional view illustrating the arrangement of the nozzles of 100 Fig. 4.

Fig. 6 is a vertical sectional view, partly in elevation, of a modified form of double stage apparatus embodying my invention.

Referring to Fig. 1, C is a characteristic 105 curve whose ordinates are quotients ob-

tained by dividing the ratios of compression in the second stage by the simultaneous ratios of compression in the first stage, and whose abscissae are degrees of vacuum at 5 the suction of the first stage expressed in inches of mercury column, referred to 30 inch barometer. The part of the curve C above the horizontal heavy line *a* and to the left of the point *b* refers to ratios of compression in the first stage which are greater than the simultaneous ratios of compression in the second stage, while all points of the curve to the right of point *b* and below the line refer to a reverse condition, in that in 10 15 20 25 30 35 40 45 50 55 60 65 70 75 80 85 90 95 100 105 110 115 120 125 130 the second stage the ratios of compression are greater than in the first stage. Throughout the curve C the total steam consumption of both stages is constant and the steam consumption of the first stage is a constant percentage of the total steam consumed in both stages.

The curve C, obtained from observations of double stage apparatus embodying my invention, shows that for varying loads on the 25 30 35 40 45 50 55 60 65 70 75 80 85 90 95 100 105 110 115 120 125 130 ejector apparatus causing in the suction inlet of the first stage ejector a vacuum higher than approximately 26 $\frac{1}{2}$ inches, and with a given steam consumption in the first stage of more than 5 per cent. of the total steam or motive fluid consumption of both stages, the ratios of compression in the first stage are greater than in the second stage.

By increasing the proportion of steam or motive fluid used in the first stage the point *b*, where the curve C intersects the line *a*, moves toward the right and may reach at least as far as the point *c* corresponding with 25 inches of vacuum or substantially one-sixth of the range from zero absolute 40 pressure to atmospheric pressure or higher.

To so proportion the double stage apparatus that the point *b* moves even farther to the right than the point *c* is, I believe, of no advantage, in that for vacua of less than 25 inches single stage apparatus may be employed to greater advantage than double stage apparatus and at higher efficiency.

The total ratio of compression of two stages of the ejector apparatus, that is, the 50 55 60 65 70 75 80 85 90 95 100 105 110 115 120 125 130 ratio of the pressure at the discharge of the second ejector to the first stage suction pressure, for example when increasing the pressure of the air from 29 inches vacuum or 1 inch absolute to atmospheric pressure or 30 inches absolute, is 30. For such a total ratio of compression, the ratio of compression in each stage, when the ratio of compression in one stage is equal to that in the other, is the square root of the total ratio of compression, and in this example approximately 5.47. And as the ratio of compression in the first stage increases above that in the second stage, the ratio of compression for this example will be in the first stage greater than 5.47, and the ratio of compression in

the second stage will be correspondingly smaller, the products of the ratios of compression in both stages equaling the simultaneous total ratio of compression.

In the example illustrated in Fig. 1, the two stage ejector apparatus is such that there is equality of the ratios of compression in both stages for a first stage suction pressure of 3.5 inches absolute. For such suction pressure, when the apparatus compresses the air to 30 inches absolute, the total ratio of compression is 8.6, and the ratio of compression in each stage is the square root of 8.6 or 2.9; and for all suction pressures less than 3.5 inches absolute the ejector apparatus will operate with a ratio of compression in the first stage greater than 2.9 and in the second stage less than 2.9, when compressing to 30 inches absolute.

My invention therefore comprises a method of and apparatus for producing and maintaining vacua of approximately 25 inches or higher and characterized by the fact that the ratio of compression in the first stage ejector is higher than the ratio of compression in the second stage, with a motive fluid consumption in the first stage which is more than 5 per cent. of the total motive fluid consumption of both stages. Under these circumstances the total motive fluid necessary for a given condition and load is less than has been attainable, so far as I am aware, with any previously practised method or apparatus.

It has been proposed to employ in the first stage of ejector apparatus a smaller ratio of compression than in the second stage in order that the amount of motive fluid delivered from the first stage into the second stage would be small and therefore require less motive fluid in the second stage, where in the motive fluid from the first stage must also be compressed to atmospheric pressure. The advantage in such method is more than compensated for by the fact that where a high ratio of compression is resorted to in any stage, as the second, the amount of motive fluid required increases very rapidly with increase in ratio of compression and increases also with the load, and the amount of motive fluid required to operate at high ratio of compression outweighs the advantage gained with low ratio of compression, as in the first stage, in effecting a saving of motive fluid in the second stage. In other words, the saving effected by using in the first stage relatively small amount of motive fluid and therefore small ratio of compression is more than counterbalanced when using in the first stage a greater amount of motive fluid and a higher ratio of compression.

Accordingly by my invention I use in the first stage a greater amount of motive fluid, more than 5 per cent. of the total motive

fluid of both stages, and in any event an amount of motive fluid insuring a ratio of compression in the first stage higher than or equal to the ratio of compression in the 5 second stage when producing high vacuum, as above 25 inches.

In Fig. 2 is shown ejector apparatus embodying my invention and suitable for carrying out my method and is in general of 10 well known construction comprising in the first stage a plurality of motive fluid nozzles N whose inlets communicate with the chamber d to which suitable motive fluid, such as steam under pressure, is delivered through 15 the opening e . These nozzles are in a chamber f having the suction inlet g communicating with the condenser or other device in which high vacuum is to be maintained. The nozzles are directed toward the diffuser 20 h which, in the example illustrated, discharges into the chamber i , which may be a condenser in which the steam or motive fluid from the first stage injector is condensed, as well understood in the art. From the 25 chamber i the elastic fluid to be compressed is delivered to the suction inlet j of the second stage comprising the nozzles N^1 whose inlets communicate with a chamber d^1 to which steam or other elastic motive fluid is 30 delivered through the passage e^1 . The nozzles N^1 are directed toward the second stage diffuser h^1 which discharges at k to atmospheric or into any desired receptacle.

To adapt this apparatus for carrying out 35 my method and to embody my invention, however, I so proportion the areas of the throats T of the nozzles N of the first stage with respect to the areas of the throats T^1 of the second stage that the sum of the areas 40 of the first stage throats T shall be such that they unitedly pass steam or motive fluid more than 5 per cent. of the total motive fluid used by the nozzles N and N^1 of both stages. Under such circumstances the ratio 45 of compression in the first stage will be greater than or at least equal to the ratio of compression of the second stage when there is at the suction inlet g of the first stage a vacuum of 25 inches or higher. When the 50 amount of air or other elastic fluid entering at g varies, the vacuum at g will correspondingly vary, the vacuum rising as the amount of elastic fluid arriving at the suction inlet decreases. And for all varying loads causing 55 at the suction inlet g a vacuum varying from 25 inches upwardly the ratio of compression in the first stage is, as stated, equal to or higher than the ratio of compression of the second stage when the steam consumption 60 by the first stage nozzles is more than 5 per cent. of the total steam consumption of both stages, under which circumstances the total steam consumption of the ejector apparatus as described will be less than when 65 in the first stage under like conditions the

ratio of compression is less than the ratio of compression of the second stage.

It will be understood that the chamber or condenser i may be used or not, as desired.

When the interstage condenser i is employed the steam or condensable fluid discharged thereinto from the diffuser h is condensed, with the result that the amount of elastic fluid to be compressed by the second stage is reduced. Where such condenser is 70 employed, the amount of motive fluid consumed in the second stage may be reduced to substantially 50 per centum of that which is necessary therein in the case where no condensation between stages takes place. There 80 fore, where a condenser i is used and the consumption of steam in the second stage is thus reduced substantially one-half, the steam consumption in the first stage will still be more than 5 per cent. of the entire steam 85 consumption, and will be a greater proportion of the total steam consumption than in the case where the inter-stage condenser is not employed.

It will be understood that in either stage 90 any suitable nozzle structure or arrangement may be employed.

For example, there may be employed the nozzle arrangement of Figs. 4 and 5, particularly in the first stage. There are in 95 this case two circular series of nozzles N and a nozzle N at the center, the nozzles increasing in length from the outside of the group toward the center; that is, the nozzle outlets approach or extend into the diffuser structure farther and farther as they are positioned farther and farther from the outside toward the center of the group.

It will be noted also as to Fig. 2 that the arrangement is similar in that the nozzles 105 increase in length toward the center. This I have found of advantage, particularly at the heavier loads, when using in the first stage a ratio of compression equal to or greater than the ratio of compression in the second 110 stage, to insure steadiness of operation, that is, to prevent periodic fluctuations in the vacuum.

By such arrangement of Figs. 2 and 4 the jets from the outer nozzles entrain by far the 115 greater part of the elastic fluid to be compressed, and the jet from the central nozzle is particularly employed for compression purposes to deliver the mixture at high velocity to the throat m of the diffuser.

In Fig. 6 I have shown a modified double stage structure in which in the first stage there is used an ordinary type of ejector similar to that used in the first stage of Fig. 2, motive fluid or steam being delivered to the chamber d through the pipe n controlled by valve o . The diffuser h of the first stage delivers the mixture of motive fluid and fluid to be compressed in divided streams through the passages p, p into the annular chambers 125 130

5 *q, q* on opposite sides of a radial jet issuing from the annular nozzle *r* formed by the disk members *s* and *t* having the throat *T*² through which motive fluid or steam is delivered from the pipe *v* controlled by the valve *w*, the pipe *r* and the valve *w* also delivering the motive fluid for the first stage to the pipe *u*.

10 The elastic fluid delivered through the passages *p, p* to the second stage apparatus is entrained by the jet from the annular nozzle *r* and compressed in the annular diffuser *w*, which delivers into the discharge casing *y* having the discharge outlet *z*.

15 In the case of Fig. 6 also it will be understood that the ratio of compression in the first stage is higher or equal to the ratio of compression in the second stage for all loads occasioning vacua of 25 inches or higher 20 with a steam consumption in the first stage of more than 5 per cent. of the total motive fluid consumed in both stages. This again is insured by causing the total area of the throats *T* of the nozzles *N* of the first stage 25 to be so proportioned to the area of throat *T*² of the second stage that at the motive fluid pressure employed the amount of motive fluid passing through the first stage nozzles is more than 5 per cent. of that consumed in both stages.

30 In the foregoing description of the motive fluid consumption in the first stage as greater than 5 per cent. of the total motive fluid consumption there has been assumed equality of 35 pressure of the motive fluid delivered to the nozzles of both stages. In case the motive fluid pressure on the first stage is less than on the second stage, the weight of motive fluid required for the first stage to maintain 40 the vacuum above 25 inches with a ratio of compression equal to or greater than the ratio of compression in the second stage will be correspondingly greater than 5 per cent. of the total steam consumption.

45 And where the motive fluid delivered to the second stage is lower in pressure than that delivered to the first stage, the motive fluid consumption of the first stage will be correspondingly lower, but in no event less 50 than 5 per cent. of the total motive fluid consumption, for practical working conditions.

55 In other words, where different motive fluid pressures are used on the different stages, the areas of nozzle throats will be correspondingly varied so that the weight of motive fluid consumed in the first stage shall nevertheless be more than 5 per cent. of the weight of the total motive fluid consumption and of a quantity suitable to maintain the ratio of compression in the first stage greater than or equal to the ratio of compression in the second stage for vacua higher than 25 inches.

60 65 In starting the apparatus hereinbefore de-

scribed, the valve or valves controlling admission of steam to both the first and second stage nozzles may be immediately opened to full extent and left in that position, and the apparatus will promptly start without fluctuations and thereafter continue in operation without fluctuation or breaking of the vacuum notwithstanding variation in load and first stage suction pressure through a great range.

70 Furthermore, by the method and apparatus hereinbefore described the desired operation is not obtainable only at a critical suction pressure, or through a very narrow variation of suction pressure, but, on the contrary, the operation is satisfactory and steady throughout wide variation in the suction pressure and load.

75 What I claim is:

1. The method of compressing elastic 85 fluid, which consists in partially compressing the same by ejector action in each of two stages, and in the first stage entraining and compressing said elastic fluid by elastic motive fluid of such quantity as to cause in 90 the first stage a ratio of compression not less than the ratio of compression in the second stage.

2. The method of compressing elastic fluid in two stages from a pressure not greater 95 than 5 inches mercury absolute to substantially atmospheric pressure, which consists in partially compressing the same by ejector action in each of two stages, and in the first stage entraining and compressing the elastic 100 fluid by elastic motive fluid whose quantity is in excess of 5 percentum of the total motive fluid consumed in both stages and such as to cause in the first stage a ratio of compression greater than the ratio of compression in the second stage.

3. The method of compressing elastic fluid from an absolute pressure less than 5 inches of mercury to substantially atmospheric pressure, which consists in partially 110 compressing the same by ejector action in each of two stages, and in the first stage entraining and compressing said elastic fluid by elastic motive fluid in excess of 5 percentum of the total motive fluid consumed 115 in both stages and such as to cause a ratio of compression greater than the ratio of compression in the second stage.

4. The method of compressing elastic fluid, which consists in partially compressing 120 the same by ejector action in each of two stages, and in the first stage entraining and compressing said elastic fluid by elastic motive fluid of such quantity as to cause in the first stage a ratio of compression greater 125 than the ratio of compression in the second stage for all first stage suction pressures less than a predetermined value and as to cause for all first stage suction pressures higher than said predetermined value a ratio of 130

compression less than the ratio of compression of the second stage, said predetermined value being within a range below 5 inches mercury absolute.

5. The method of compressing elastic fluid, which consists in partially compressing the same by ejector action in each of two stages, and in the first stage entraining and compressing said elastic fluid by elastic motive fluid of such quantity as to cause in the first stage a ratio of compression greater than the ratio of compression in the second stage for all first stage suction pressures less than a predetermined value and as to cause for 10 all first stage suction pressures higher than said predetermined value a ratio of compression less than the ratio of compression of the second stage, said predetermined value being within a range from zero absolute 15 pressure to approximately one-sixth of the pressure to which the elastic fluid is compressed.

6. The method of compressing elastic fluid in two stages from a pressure less than 25 5 inches mercury absolute to substantially atmospheric pressure, which consists in entraining and compressing in the first stage said elastic fluid by elastic motive fluid of such quantity as to cause in the first stage 30 a ratio of compression greater than the ratio of compression in the second stage for all first stage suction pressures within a range below 5 inches mercury absolute, condensing the condensable fluid delivered from 35 the first stage, and in the second stage entraining and compressing the uncondensed fluid by elastic motive fluid and delivering it at substantially atmospheric pressure.

7. The method of compressing elastic 40 fluid in two stages from a pressure below 5 inches mercury absolute to substantially atmospheric pressure, which consists in entraining and compressing in the first stage said elastic fluid by elastic motive fluid of 45 such quantity as to cause in the first stage a ratio of compression which is equal to the ratio of compression in the second stage for a first stage suction pressure less than 5 inches mercury absolute and greater than 50 the ratio of compression in the second stage for all first stage suction pressures in a range below said first named first stage suction pressure, condensing the condensable fluid delivered from the first stage, and in the 55 second stage entraining and compressing the uncondensed fluid by elastic motive fluid and delivering it at substantially atmospheric pressure.

8. The method of compressing elastic 60 fluid, which consists in partially compressing the same by ejector action in each of two stages, and in the first stage entraining and compressing said elastic fluid by elastic motive fluid in excess of 5 percentum of the 65 total motive fluid consumed in both stages

and such as to cause a ratio of compression not less than the ratio of compression in the second stage, said predetermined value being within a range below 5 inches mercury absolute.

9. Two-stage ejector apparatus for compressing elastic fluid from an absolute pressure less than 5 inches of mercury to substantially atmospheric pressure comprising two ejectors connected in series and each 70 comprising nozzle and diffuser structure, the total throat area of the nozzle structure of the first stage being so proportioned with respect to the total throat area of the nozzle structure of the second stage that the ratio 75 of compression in the first stage is not less than the ratio of compression in the second stage and the motive fluid passed through the nozzle structure of the first stage is greater than 5 percentum of the motive 80 fluid consumed in both stages.

10. Multi-stage ejector apparatus comprising two ejectors connected in series and each comprising nozzle and diffuser structure, the total throat area of the nozzle 90 structure of the first stage being such that the ratio of compression in the first stage is not less than the ratio of compression in the second stage.

11. Two-stage ejector apparatus for compressing elastic fluid to substantially atmospheric pressure, comprising two ejectors connected in series and each comprising nozzle and diffuser structure, the total throat area of the nozzle structure in the first stage 100 being such that the ratio of compression in the first stage is greater than the ratio of compression in the second stage for first stage suction pressures within a range below 5 inches mercury absolute.

12. Multi-stage ejector apparatus comprising two ejectors connected in series and each comprising nozzle and diffuser structure, the nozzle throat areas of the two stages being so proportioned with respect to each 110 other that with varying first stage suction pressure the ratio of compression in the first stage varies through values greater than and less than the simultaneous ratio of compression in the second stage.

13. Multi-stage ejector apparatus comprising two ejectors connected in series and each comprising nozzle and diffuser structure, the nozzle throat areas of the two stages being so proportioned with respect to each other 115 that the ratios of compression in both stages are equal for a predetermined first stage suction pressure and unequal for all other first stage suction pressures.

14. Multi-stage ejector apparatus comprising two ejectors connected in series and each comprising nozzle and diffuser structure, the nozzle throat areas of the two stages being so proportioned with respect to each other 120 that the ratios of compression in both stages are equal for a predetermined first stage suction pressure and unequal for all other first stage suction pressures.

- are equal for a predetermined first stage suction pressure and unequal for all other first stage suction pressures, said predetermined pressure lying within a range below 5 inches mercury absolute.
15. Multi-stage ejector apparatus comprising two ejectors connected in series and each comprising nozzle and diffuser structure, the nozzle structure in the first stage comprising a group of nozzles increasing in length toward the center of the group, the total throat area of the nozzle structure of the first stage being so proportioned with respect to the total throat area of the nozzle structure of the second stage that the ratio of compression in the first stage is not less than the ratio of compression in the second stage and the motive fluid passed through the nozzle structure of the first stage is greater than 5 percentum of the motive fluid consumed in both stages.
16. Multi-stage ejector apparatus comprising two ejectors connected in series and each comprising nozzle and diffuser structure, the nozzle structure in the first stage comprising a group of nozzles increasing in length toward the center of the group, the total throat area of the nozzle structure of the first stage being such that the ratio of compression in the first stage is not less than the ratio of compression in the second stage.
17. Multi-stage ejector apparatus comprising two ejectors connected in series and each comprising nozzle and diffuser structure, the nozzle structure in the first stage comprising a group of nozzles increasing in length toward the center of the group, the total throat area of the nozzle structure of the first stage being such that the ratio of compression in the first stage is greater than the ratio of compression in the second stage for first stage suction pressures lying within a range below 5 inches mercury absolute.
18. Two-stage ejector apparatus for compressing elastic fluid to substantially atmospheric pressure comprising two ejectors connected in series and each comprising nozzle and diffuser structure, the nozzle structure in the first stage comprising a group of nozzles increasing in length toward the center of the group, the nozzle throat areas of the two stages being so proportioned with respect to each other that the ratio of compression in the first stage is greater than the ratio of compression in the second stage for first stage suction pressures varying within a range below 5 inches mercury absolute.
19. Multi-stage ejector apparatus for producing high vacuum and operating with a total ratio of compression greater than 8.6 comprising two ejectors connected in series and each comprising nozzle and diffuser structure, the total throat area of the nozzle structure of the first stage being so proportioned with respect to the total throat area of

the nozzle structure of the second stage that the ratio of compression in the first stage is greater and the ratio of compression in the second stage less than 2.9 for first stage suction pressures which are less than 3.5 inches mercury absolute.

20. Multi-stage ejector apparatus comprising two ejectors connected in series and each comprising nozzle and diffuser structure, the nozzle structure in the first stage comprising a group of nozzles increasing in length toward the center of the group, the nozzle throat areas of the two stages being so proportioned with respect to each other that with varying first stage suction pressure the ratio of compression in the first stage varies through values greater and less than the simultaneous ratio of compression in the second stage.

21. Multi-stage ejector apparatus for compressing elastic fluid to substantially atmospheric pressure comprising two ejectors in series and each comprising nozzle and diffuser structure, the second stage ejector comprising an annular nozzle and an annular diffuser, the total throat area of the nozzle structure of the first stage being so proportioned with respect to the throat area of the annular nozzle of the second stage that the ratio of compression in the first stage is not less than the ratio of compression in the second stage for first stage suction pressures varying within a range below 5 inches mercury absolute.

22. Multi-stage ejector apparatus for compressing elastic fluid to substantially atmospheric pressure comprising two ejectors in series and each comprising nozzle and diffuser structure, the second stage ejector comprising an annular nozzle and an annular diffuser, the total throat area of the nozzle structure of the first stage being so proportioned with respect to the throat area of the annular nozzle of the second stage that the ratio of compression in the first stage is not less than the ratio of compression in the second stage for first stage suction pressures varying within a range below 5 inches mercury absolute and that the motive fluid consumption in the first stage is greater than 5 percentum of the total motive fluid consumption in both stages.

23. Multi-stage ejector apparatus comprising two ejectors connected in series and each comprising nozzle and diffuser structure, the nozzle structure in the first stage comprising a group of nozzles increasing in length toward the center of the group, the second stage ejector comprising an annular nozzle and an annular diffuser, the total throat area of the nozzle structure of the first stage being so proportioned with respect to the area of the throat of the annular nozzle of the second stage that the ratio of compression in the first stage is greater than the

ratio of compression in the second stage for any first stage suction pressure within a range below 5 inches mercury absolute.

24. Two-stage ejector apparatus for compressing elastic fluid from an absolute pressure less than 5 inches of mercury to substantially atmospheric pressure comprising two ejectors connected in series and each comprising nozzle and diffuser structure, the 10 total throat area of the first stage nozzle structure being so proportioned with respect to the total throat area of the nozzle structure of the second stage that for a predetermined first stage suction pressure the 15 ratio of compression in the first stage is equal to the ratio of compression in the second stage and the ratio of compression in the first stage greater than the ratio of compression in the second stage for all first stage 20 suction pressures less than said first named first stage suction pressure.

25. Two-stage ejector apparatus for compressing elastic fluid to substantially atmospheric pressure comprising two ejectors connected in series with each other and each 25 comprising nozzle and diffuser structure, means between said ejectors for condensing fluid discharged from the first ejector and discharging uncondensed fluid to the second ejector, the total throat area of the nozzle 30 structure of the first ejector being so proportioned with respect to the total throat area of the nozzle structure of the second ejector that the ratio of compression in said first ejector is greater than the ratio of compression in the second ejector for all first stage suction pressures within a range below 5 inches mercury absolute. 35

In testimony whereof I have hereunto affixed my signature this 13th day of July, 40 1917.

ROBERT SUCZEK.
